(57) **CLAIM**

The ornamental design for the slideable connector component, as shown and described.

DESCRIPTION

FIG. 1 is a front perspective view of one embodiment of my slideable connector component.

FIG. 2 is a rear perspective view of my slideable connector component shown in FIG. 1.

FIG. 3 is a top plan view of the embodiment of my slideable connector component shown in FIG. 1.

FIG. 4 is a front view of the embodiment of my slideable connector component shown in FIG. 1.

FIG. 5 is a left side elevation view of the embodiment of my slideable connector component shown in FIG. 1, and the right side is a mirror image of the left side.

FIG. 6 is a rear view of the embodiment of my slideable connector component shown in FIG. 1; and,

FIG. 7 is a bottom plan view of the embodiment of my slideable connector component shown in FIG. 1.

The broken lines showing an opening are for the purposes of illustrating environment and form no part of the claimed design.
